UNITED STATES PATENT OFFICE.

LEONARD BARTLETT, OF NEW YORK, N. Y., ASSIGNOR TO AMERICAN CORK AND SEAL COMPANY, A CORPORATION OF MAINE.

SEAL FOR BOTTLES.

No. 867,904.

Specification of Letters Patent.

Patented Oct. 8, 1907.

Application filed January 18, 1907. Serial No. 352,885.

To all whom it may concern:

Be it known that I, LEONARD BARTLETT, a citizen of the United States, residing at New York, borough of Brooklyn, in the county of Kings and State of New York, have invented a new and useful Seal for Bottles, of which the following is a specification.

This invention relates to seals for bottles, and has for its object,—first, to provide a sealing cap with a soft or puncturable center so constructed that no leakage can occur between the locking rim, and the metal closing the center; second, to provide a seal of the character described having a lining, or interior part containing the minimum amount of material consistent with perfect safety in order to secure a tight seal; and, 15 third, to provide an interior lining so constructed that a sealing ring may be used, such as rubber, without liability of having the contents of the bottle come in contact therewith.

The invention is illustrated in the accompanying drawing, in which—

Figure 1, represents a central, vertical section of the head of a bottle having my improved seal applied thereto; Fig. 2, is a view of a portion of the seal on an enlarged scale, before being applied to a bottle; Fig. 3, is 25 a view of a modified form of seal; Fig. 4, is a view of the same applied to a bottle; Fig. 5, is a view of another modified form of seal; and Fig. 6, is a view of the same applied to a bottle.

In the accompanying drawing the several parts of 30 my invention are indicated by numerals of reference; and in practice I provide a bottle seal comprising an outer ring, or clamping member 7, which may be composed of tin plate, commonly called "tin", and an inner member 8, of different material, preferably composed of non-corrosive metal, as aluminum.

The member 7 is preferably provided with an open center 9, so that the inner member 8 is exposed at this point, and as the inner member may be composed of very thin aluminum, or very thin metal of any kind, 40 it may be readily punctured to gain access to the contents of the bottle in the absence of a regular opening tool.

The member 7, is provided with a skirt which may be of any well known form for clamping upon a bottle, but 45 I prefer the stepped skirt shown in a companion application executed by me this day (Serial No. 352,884, filed Jan. 18, 1907); and may be locked upon a bottle 10, by any suitable clamping machine.

In placing the seal upon a bottle, I prefer to use a 50 ring 11, so as to leave the center exposed to the contents of the bottle, and that there may be no part of the gasket in the way should entrance to the contents be made through the seal by puncturing the member 8.

The member 8 need not extend to the bottom of the 55 member 7, as it is sufficient if this member extend be-

yond the gasket 11, to engage the sides of the locking shoulder 12 of the bottle 10, as in this way the edges of the member 8 will be frictionally held by the shoulder 12 in addition to the pressure placed upon the same by pressure between the gasket and the member 7; and 60 the center of the member 8 will be held over the opening 10 as a diaphragm, so that all the strength that is required in the member 8 is tensile strength, and for this reason it may be made much thinner than if a certain amount of rigidity were required. This not only 65 saves metal, but makes it much easier to puncture the member 8 if it is desired to open the bottle in that way.

In order to hold the member 8 in place within the member 7 before being placed on the bottle, I prefer to provide a series of inward projections 13, against 70 which the edges of the member 8 rest; and where a cork ring is used for a gasket, these projections may also sustain the gasket in place before being applied to the bottle, as shown in Fig. 2.

In placing the member 8 within the member 7, I 75 prefer to force the metal up within the opening 9, as shown at 14, so that the top of the part covering this opening will be on the same plane as the top of the member 7, thereby adding to the appearance of the cap, and eliminating any receptacle for the accumulation of dirt.

In the construction shown in Figs. 3 and 4, the member 8', is provided with an annular rib 15, greater in diameter than the opening 9, in the member 7, and also greater in diameter than the throat of the bottle 85 16, so that this rib will engage the lip 17, of the bottle. This rib is preferably provided with a vertical outer edge 18, and an inclined inner edge 19, and a rubber gasket 20, is mounted around this rib, being held thereon by friction caused by slightly stretching the 90 rubber in placing the same on the rib. When this seal is placed upon the bottle, the member 8' being very thin, the rib 15 will crush upon the lip of the bottle at the same time the gasket 20, is forced into sealing contact with the lip, and the rib being of 95 non-corrosive metal, will prevent the contents of the bottle reaching the rubber gasket so that they will not be contaminated by the rubber. At the same time, the edges of the member 8' will engage the shoulder 12, of the bottle, and the entire member will 100 be firmly held within the member 7, as previously described in connection with the cork gasket.

In the construction shown in Figs. 5, and 6, an annular rib 15', and a second annular rib 22, are formed in the member 8'', and the gasket 20', is 105 mounted in the groove formed between these ribs, as clearly shown in the drawing. By providing the two ribs the gasket will be more firmly held in place when pressed upon the lip of a bottle. The construction is otherwise the same.

It will thus be seen that I have provided a seal for bottles in which there is no chance for leakage between the inner and outer members owing to the fact that the inner member extends beyond the gasket to engage the locking shoulder; and by engaging the locking shoulder, sufficient friction can be produced on the inner member to prevent the same being blown through the opening in the outer member even if very thin material is used, thereby saving material required for the formation of the inner member; and making the same more easily puncturable. I also save material by extending the inner member only far enough to engage the locking shoulder without extending the same to the bottom of the skirt of the outer member. I have also provided simple and efficient means in connection therewith to use a rubber gasket instead of cork without endangering the contents of the bottle.

Having thus described my invention, what I claim as new and desire to secure by Letters Patent of the United States, is—

1. A seal for bottles comprising an outer member having an open center, an inner member closing said center, and a gasket, one of said members being provided with means to hold said outer and inner member together when detached from a bottle, said inner member extending beyond said gasket to engage the locking shoulder of a bottle.
2. A seal for bottles comprising an outer member having an open center, an inner member extending across said center, and a gasket for engaging the lip of a bottle, said inner member being extended to engage the locking shoulder of a bottle beyond said gasket, said outer member having means to hold the inner member in position.
3. A bottle seal comprising an outer, locking member, and an inner member of non-corrosive material, said inner

member being provided with a rib adapted to engage the lip of a bottle, and being extended to engage the outer surface of the locking shoulder of a bottle, and a gasket mounted around said rib, for the purpose set forth. 40

4. A seal for bottles comprising an outer member having an open center, and a clamping skirt, an inner member closing said center composed of non-corrosive material, said inner member being provided with a rib adapted to engage the lip of a bottle, and being extended to engage the outer surface of the locking shoulder of a bottle, and a gasket mounted on said rib, as and for the purpose set forth. 45

5. A seal for bottles comprising an outer member of rigid material having an open center, an inner member of different material closing said center, and extending to engage the outer surface of the locking shoulder of a bottle, said inner member having two annular ribs formed therein adapted to engage the lip of a bottle, and a rubber gasket mounted between said ribs, for the purpose set forth. 55

6. A seal for bottles comprising an outer member of rigid material, an inner member, of yielding, non-corrosive material having two annular ribs formed therein adapted to engage the lip of a bottle, and a rubber gasket mounted between said ribs, for the purpose set forth. 60

7. A seal for bottles comprising an outer member of rigid material having an open center, an inner member of yielding, non-corrosive material closing said center, and extending to engage the outer surface of the locking shoulder of a bottle, said inner member having two annular ribs formed therein adapted to engage the lip of a bottle, and a rubber gasket mounted between said ribs, and held therein by friction, as and for the purpose set forth. 65

In testimony whereof I have signed my name to this specification in the presence of two subscribing witnesses.

LEONARD BARTLETT.
